DAMPER CONSTRUCTION

Erving B. Morgan, Grand Rapids, Mich., assignor
to American Seating Company, Grand Rapids,
Mich., a corporation of New Jersey

Application November 30, 1949, Serial No. 130,183

9 Claims. (Cl. 98—41)

1

The present invention relates to damper constructions and more particularly to damper constructions used in ventilation flues through the cement floors of buildings such as theatres, auditoriums and the like.

The primary objects of the invention are to provide a damper construction in which the damper plate is installed in a sleeve which is set in the cement floor of a theatre or the like at the time the cement is poured, and to provide such a damper construction which is efficient and which is economically made, and quickly assembled, from a few simply constructed parts.

An illustrative embodiment of the invention is shown in the accompanying drawings, wherein:

Figure 1 is a view, partly in front elevation and partly in section taken on line 1—1 of Figure 2, of the lower end of a theatre chair supporting standard and a baffled ventilator hood secured thereto, and of the theatre floor and damper construction of the present invention;

Figure 2 is a view of the same shown partly in side elevation and partly in section taken on line 2—2 of Figure 1;

Figure 3 is an enlarged horizontal sectional view through the damper construction taken on line 3—3 of Figure 1 and showing the damper plate in a horizontal position;

Figure 4 is a top plan view of the damper plate per se with parts thereof shown in their normal positions in dotted lines and in inwardly sprung positions in solid lines;

Figure 5 is an enlarged fragmentary sectional view of parts of the damper construction, taken on section line 5—5 of Figure 3, and showing certain parts in their assembled positions in full lines and in intermediate positions during assembly in dotted lines; and

Figure 6 is a top plan view of a slightly modified damper plate, shown per se.

It is common practice in theatres having cement floors to provide a plenum chamber beneath the cement floor with ventilation flues extending through the floor, through which flues conditioned air is supplied to the theatre from the plenum chamber. Dampers are customarily installed in the ventilation flues. These dampers are not intended for the purpose of varying the flow of air through the flues (although corrective adjustment can be made after installation), but are rather intended for permanent setting to adjust the flow of air through the numerous flues so that a uniform flow of air is supplied through each flue regardless of its proximity to the source of supply to the plenum chamber. The present

2

invention is in the nature of an improvement over the damper construction shown in Patent No. 2,206,749, issued July 2, 1940, to my assignee; and also utilizes certain features disclosed in Patent No. 2,165,593 issued July 11, 1939, likewise to my assignee.

Referring now in detail to the drawings in this case, Figures 1, 2 and 3 show a cement theatre floor 10 having a plenum chamber therebeneath indicated by the numeral 11, and having flue 12 therethrough. Such flues are usually located directly beneath certain of the chair supporting standards in a theatre, one of which is indicated fragmentarily in Figures 1 and 2 and is designated 13. A ventilating hood generally designated 14 comprises complementary halves secured together on opposite sides of the standard 13 by means of a bolt 15, said hood being directly over the flue 12 and being provided for the purpose of diffusing the conditioned air passing upwardly through said flue.

The damper plate 16, which will be more particularly described hereinafter, is mounted in a sleeve 17 which is preferably integrally cast from grey iron and has a laterally extending lower-peripheral flange 18. A sleeve extension 19 is desirably made of sheet metal wrapped around the upper end of the sleeve 17 and having its meeting ends secured together as by means of rivets 20, said sleeve extension 19 being secured to the sleeve 17 as by means of screws or rivets 21 (see Figure 1). The height of the cast metal sleeve 17 is the same for all installations, whereas the height of the sleeve extension 19 may be varied so that the total height of sleeve and sleeve extension assembled is equal to the thickness of the floor in a particular installation. This assembly is set in position on a temporary sub-floor, either with or without the damper plate 16 assembled thereto, prior to pouring of the cement floor, so that the sleeve and sleeve extension are permanently embedded in the floor and form the ventilation flue 12 at the time the cement is poured.

The damper 16 comprises a unitary plate preferably of cast iron, which is cast with circuitous slots 22 therethrough which form diametrically opposed arms 23 which are laterally springable relative to the main body of the damper plate. Reinforcing ridges 24 are cast in the plate alongside the circuitous slots 22 to insure against breakage of the arms 23 from the main body of the damper plate 16. The arms 23 have integrally cast, diametrically opposed, laterally extending cylindrical pins 25 thereon, and integrally cast collars 26 adjacent said pins 25.

The sleeve 17 has diametrically opposed cylindrical openings therethrough forming bearings 27 for the pins 25 of the damper plate, and the sleeve 17 is also provided with longitudinally extending guide grooves 28 in the inner wall thereof adjacent said bearings 27.

The normal distance between the ends of the pins 25 of the damper plate is somewhat greater than the diameter of the sleeve 17 at the bearings 27. In assembling the damper to the sleeve, the arms 23 of the damper plate are sprung inwardly as indicated in full lines in Figure 4 so that the pins 25 may be simultaneously inserted within the respective guide grooves 28, as indicated by dotted lines in Figure 5. It will be seen that the damper may thus be inserted in the sleeve from either the top or the bottom, and in either case the damper is moved longitudinally in the sleeve until the pins 25 arrive at the bearings 27 whereupon the arms 23 of the damper plate spring outwardly to rotatably seat the pins 25 in the bearings 27. Collars 26 on the damper plate engage the inner wall of the sleeve 17 adjacent the guide grooves 28 and provide sufficient friction to maintain the damper permanently in its manually set position for adjusting the flow of air as required for the particular flue in which the damper is mounted. The damper plate may also desirably be cast as indicated in Figure 6, wherein the arms 23 of the damper plate 16 normally project laterally outwardly from the main body of the damper plate, thus to provide more friction between the damper plate and the sleeve when these parts are assembled.

As here shown the damper plate 16 is oblong in form, with semicircular ends, and the sleeve 17 is correspondingly shaped in cross-section. However this form may be varied if desired, and other details of the construction shown may be altered or omitted, without departing from the spirit of invention as defined by the following claims.

I claim:

1. In a damper construction for a flue: a sleeve in the flue having diametrically opposed openings therein forming bearings; and a damper comprising a unitary plate having circuitous slots therethrough forming diametrically opposed laterally springable arms provided with laterally extending pins thereon, the normal distance between the ends of said pins being greater than the inner diameter of said sleeve at the bearings, and said arms being springable inwardly to permit insertion of the damper in the sleeve and being thereafter springable outwardly to rotatably seat said pins in said bearings.

2. In a damper construction for a flue: a sleeve in the flue having diametrically opposed openings therein forming bearings; and a damper comprising a unitary cast metal plate having circuitous slots therethrough forming diametrically opposed laterally springable arms provided with laterally extending pins thereon, the normal distance between the ends of said pins being greater than the inner diameter of said sleeve at the bearings, and said arms being springable inwardly to permit insertion of the damper in the sleeve and being thereafter springable outwardly to rotatably seat said pins in said bearings.

3. In a damper construction for a flue: a sleeve in the flue having diametrically opposed openings therein forming bearings; and a damper comprising a unitary cast metal plate having circuitous slots therethrough forming diametri-

cally opposed laterally springable arms provided with laterally extending pins thereon and said plate having reinforcing ridges cast therein alongside said circuitous slots, the normal distance between the ends of said pins being greater than the inner diameter of said sleeve at the bearings, and said arms being springable inwardly to permit insertion of the damper in the sleeve and being thereafter springable outwardly to rotatably seat said pins in said bearings.

4. In a damper construction for a flue: a sleeve in the flue having diametrically opposed openings therethrough forming bearings and having longitudinal guide grooves in the inner wall of the sleeve adjacent said bearings respectively; and a damper comprising a plate having circuitous slots therethrough forming diametrically opposed laterally springable arms provided with laterally extending pins thereon, the normal distance between the ends of said pins being greater than the inner diameter of the sleeve at the bearings, and said arms being springable inwardly to permit simultaneous insertion of said pins in the guide grooves and being thereafter springable outwardly to rotatably seat said pins in said bearings.

5. In a damper construction for a flue: a sleeve in the flue having diametrically opposed openings therethrough forming bearings and having longitudinal guide grooves in the inner wall of the sleeve adjacent said bearings respectively; and a damper comprising a unitary cast metal plate having circuitous slots therethrough forming diametrically opposed laterally springable arms provided with laterally extending pins thereon, the normal distance between the ends of said pins being greater than the inner diameter of the sleeve at the bearings, and said arms being springable inwardly to permit simultaneous insertion of said pins in the guide grooves and being thereafter springable outwardly to rotatably seat said pins in said bearings.

6. In a damper construction for a flue: a sleeve in the flue having diametrically opposed openings therethrough forming bearings and having longitudinal guide grooves in the inner wall of the sleeve adjacent said bearings respectively; and a damper comprising a unitary cast metal plate having circuitous slots therethrough forming diametrically opposed laterally springable arms provided with laterally extending pins thereon, the normal distance between the ends of said pins being greater than the inner diameter of the sleeve at the bearings, and said arms springable inwardly to permit simultaneous insertion of said pins in the guide grooves and being thereafter springable outwardly to rotatably seat said pins in said bearings; and collars cast on said damper plate adjacent said pins and bearing against the inner walls of the sleeve adjacent said guide grooves in the assembled position of the damper within the sleeve.

7. In a damper construction for a flue: a sleeve in the flue having diametrically opposed openings therethrough forming bearings and having longitudinal guide grooves in the inner wall of the sleeve adjacent said bearings respectively; and a damper comprising a unitary cast metal plate having circuitous slots therethrough forming diametrically opposed laterally springable arms provided with laterally extending pins thereon and said plate having reinforcing ridges cast therein alongside said circuitous slots, the normal distance between the ends of said pins being greater than the inner diameter of the

sleeve at the bearings, and said arms being springable inwardly to permit simultaneous insertion of said pins in the guide grooves and being thereafter springable outwardly to rotatably seat said pins in said bearings; and collars cast on said damper plate adjacent said pins and bearing against the inner walls of the sleeve adjacent said guide grooves in the assembled position of the damper within the sleeve.

8. In a damper construction for a flue: a sleeve in the flue; a damper comprising a unitary plate having circuitous slots therethrough forming diametrically opposed laterally springable arms; and cooperating pin and bearing connections on said sleeve and said arms, said arms being springable inwardly to permit insertion of the damper in the sleeve and being thereafter springable outwardly to rotatably engage said pin and bearing connections.

9. In a damper construction for a flue: a sleeve 20 in the flue; a damper comprising a unitary cast

metal plate having circuitous slots therethrough forming diametrically opposed laterally springable arms; and cooperating pin and bearing connections on said sleeve and said arms, said arms being springable inwardly to permit insertion of the damper in the sleeve and being thereafter springable outwardly to rotatably engage said pin and bearing connections.

ERVING B. MORGAN.
